UNITED STATES PATENT OFFICE.

CHESTER J. SMITH, OF JAMESTOWN, NEW YORK.

CALCULATING-MACHINE.

1,224,333.

Specification of Letters Patent.

Patented May 1, 1917.

Application filed November 12, 1915. Serial No. 61,143.

To all whom it may concern:

Be it known that I, CHESTER J. SMITH, a citizen of the United States, residing at the city of Jamestown, in the county of Chautauqua and State of New York, have invented certain new and useful Improvements in Calculating-Machines, of which the following, taken in connection with the accompanying drawings, is a specification.

10 The invention relates to calculating machines and particularly for the price of commodities, though the device is not necessarily restricted to this specific purpose; and the object of the improvement is to 15 provide a simple and convenient mechanism which may be manufactured at low cost, having a supported spring rate strip adjacent to tabulated tables on rollers and a visible inaccessible pointer adjustably 20 movable only from the exterior of the case and which adjustably rests upon said rate strips, on which, for example, the rate plate gives the price per yard and the table on the computation sheet on the rollers shows 25 the total amount for a given number of yards or inches, thus by turning the rollers the charge for three and one-eighth yards at fifty-four cents per yard is shown at once to be a dollar and sixty-nine cents; 30 and the invention consists in the novel features and combinations hereinafter set forth and claimed.

In the drawings, Figure 1 is a perspective view of the improved machine with the 35 casing removed showing the construction of the frame for holding the calculating mechanism. Fig. 2 is a top plan view of the machine, a portion of the casing being shown in section with the top flange re- 40 moved to show the arrangement of the different parts. Fig. 3 is a plan view of one of the spring rate strips, the central portion being broken away. Fig. 4 is a plan view of the spirally grooved rod for 45 adjusting the movable pointer; and Fig. 5 is a plan view of the pointer showing the opening in the ends thereof for the rate figures; and Fig. 6 is an edgewise view of the same showing the lug and the projection 50 therein for engaging the spiral groove of the adjusting rod. Fig. 7 is a sectional view at line X-X in Fig. 2, showing the arrangement of the parts; and Fig. 8 is a sectional view at line Y-Y in Fig. 2, 55 showing the arrangement of the operating gears on the ends of the roller journals.

Fig. 9 is a vertical sectional view at line Z-Z in Fig. 2. Fig. 10 is a perspective view of one end of one of the rollers; and Fig. 11 is a similar view of the opposite end. 60 Fig. 12 is a plan view of one of the knobs and the gear attached thereto, the gear being shown both in edgewise and flat elevation.

Like characters of reference refer to corresponding parts in the several views.

The numeral 15 designates the sheet metal casing which is preferably made with a removable bottom 16 which supports the frame 17 thereon. The top of the casing 70 15 is formed with an inturned flange 18 to provide a central opening which is covered by a glass 19, which glass is held in place by the frame 17 to cover the interior mechanism of the machine with full view of 75 the recording elements.

The frame 17 is composed of the side plates 20 and front end plate 21 and rear end plate 22 which are preferably attached to one another by means of the slots 23 in 80 the side plates and oppositely turned pairs of lugs 24 on the end plates, thereby attaching said end plates to said side plates a spaced distance from the ends of the side plates 20 to provide for the gearing and 85 journals. The side plates 20 are held firmly in position a spaced distance from the inner walls of the casing 15 by means of the spaced struck out lugs 25 at both the front and rear ends, the length of the lugs 25 90 and the size of the casing or box 15 being proportioned to receive said lugs therein and hold the supporting frame 17 for the calculating mechanism.

The calculating mechanism is supported 95 upon the end plates 21 and 22 and consists of the two pairs of rollers 26 and 27, the sheets 28 and 29, the rate strips 41 and pointer 43. Each pair of rollers 26 and 27 is placed vertically one above the other, and 100 the sheets 28 and 29 with the calculations thereon are attached to the rollers 26 and 27 in lengthwise grooves and rolled upon said rollers so that they roll freely backward and forward from one roller to the 105 other according to the direction in which said pairs of rollers are turned.

The rollers 26 and 27 are substantially alike having bearing pins or journals 30 at the rear end and 31 at the front end, and 110 have suitable end flanges 34 to hold the sheets 28 and 29 in line as they roll and re-

roll. A central partition 32 is provided between the two pairs of rolls 26 and 27 and is attached to the end plates 21 and 22 by means of slots 23 and oppositely turned lugs 5 24 in the same manner that the end plates 21 and 22 are attached to the side plates 20.

The rollers 26 and 27 are turned by means of connecting gearing for each pair of rolls and knobs for turning said pairs, thus a 10 small gear 33 is provided on the journal 31 of each of the rolls 26 and 27, and each of the pairs of gears 33 are connected by an intermeshing large gear 35. The large gear 35 is attached to the shaft of a knob 36 15 which shaft has a journal 37 which is revolvably mounted in the front plate 21 so that by manually turning the knob 36 in either direction the sheets 28 and 29 are rolled from one to the other of the rollers 26 and 27. In order to hold the shaft 38 of the 20 knob 36 firmly in line, a plate 39 is provided on the front of plate 21 extending between the inner walls of the side plates 20 and is attached thereto by screws 40. The 25 large and small gears 33 and 35 rotate the rollers 26 and 27 at high rate of speed thereby quickly turning to any desired row of figures on said sheets.

The rates or prices are placed upon thin 30 strips of spring sheet metal 41 in line with the computation figures on the sheets and preferably each side of each roll though one side of each of said rolls is sufficient where there are only a few rates and computations. Should, however, the number of 35 rates and computations be largely increased the strips 41 on both sides of the rollers 26 and 27 may be used. The strips 41 are supported in slots or elongated openings 42 in 40 the end plates 21 and 22, the ends of the strips 41 being reduced in width so that they may turn slightly if it is necessary in order to accommodate said rate strips to the increase in size of the top rolls as the sheets 28 45 and 29 are rolled thereon. This is usually, however, but a slight increase and is accommodated by the spring of the sheet metal in the strips 41. The sheet metal strips 41 are cut away at each end on the side toward the 50 roll and inserted in the holes 42 in each end by springing said strips 41 sidewise sufficiently to permit the ends entering said holes 42.

A pointer 43 is provided having openings 55 44 therein to exhibit the desired rate numeral and to shut out the rate numerals each side thereof so as to preclude liability to error in the computation. The pointer 43 is provided with a downwardly projecting 60 lug 45 which has the hole 46 therethrough with the inwardly projecting lug 47 therein. A spirally grooved shaft 48 is rotatively mounted in the end plates 21 and 22 midway between the two top rollers 26 and 27 65 over the upper edge of the central partition

32 of the frame 17. The spiral groove 49 fits the projection 47 so that as the shaft 48 is rotated the pointer 43 travels backward and forward in the groove 49. In order that the pointer 43 may travel freely or float 70 and not dig its points into the sheets 28 and 29, one or both of its outer ends are supported upon the rate strips 41 at each side. Resting freely in this position it slides backward and forward on said rate strips with 75 perfect freedom and is consequently always in close proximity thereto so that the desired rate numeral is quickly and easily found.

As shown in section in Fig. 7, the pointer 80 43 is balanced on rod 48 to tilt in either direction being shown with one end resting upon one of the spring rate strips 41 and the other end tilted above the rate strip 41 on the opposite side of the grooved rod 48 85 with a space between said rate strip 41 and the pointer 43. When the top rolls are wound equally and sufficiently large the balanced pointer 43 will stand level and the inner edges of the rate strip 41 will spring or turn sufficiently for the enlargement. This construction of the pointer 43 in combination with the spring rate strip 41 90 permits any inequality in the increase and decrease in the size of the top rolls each side 95 of the spiral rod, yet the spring rate strips 41 are in constant contact with the rollers even though unequal sized and the pointer adapts to said inequality by tipping to one side sufficiently to accommodate the same. 100 It will therefore be seen that I have a balanced pointer on the spiral control rod 48 and is adjustable to any of the changing conditions in the sizes of the rolls caused by the unequal winding of the sheets thereon for different calculations. 105

A small gear 50 is attached to the front end of the shaft 48 and a large gear 51 is mounted on plates 39 and 21 on a suitable shaft 53 upon the outer end of which a knob 110 52 is attached to provide for the rapid manual turning of the shaft 48, the large gear 51 insuring the rapid rotation of said spirally grooved shaft.

In assembling the calculating mechanism 115 the rollers 26 and 27 are rotatively mounted in the end plates 21 and 22 along with the shaft 48 upon which the pointer 43 is placed. The central partition 32 and side plates 20 are then attached to the end plates 21 and 22 by the insertion of the lugs 24 through the slots 23 and the spreading of said lugs 24. The gears 33 and 50 are then attached to the shafts 38 and 53. The plate 39 is then inserted between the side plates 20 and 120 fastened with the screws 40.

The gears 35 and 51 are slipped into place as nearly as possible in alinement with the holes through the plate 39 and in the end plate 21, after which the frame 20 with the 125

- portions of the mechanism thus far attached thereto is inserted in the outer casing which is placed bottom upward for that purpose. Holes are provided in the outer casing 15 5 in alinement with the holes in the plate 39 and end plate 21 so that the shafts 38 and 53 of the knobs 36 and 52 may be inserted through said holes, and the inner end 37 of the shaft 38 will be inserted through the hub 10 of the gear 35 on each side and engage the hole in the end plate 21. The set screws are then turned fast in the hubs 35, thereby attaching the knobs 36 firmly to the gears 35 so that said gears are turned by said 15 knobs. In like manner the gear 51 is attached to shaft 53 and meshes in gear 50 thereby turning said gear. After the gears 35 and 51 and knobs 36 and 52 are assembled the bottom 16 is fastened in place 20 by means of suitable screws thereby holding all the parts firmly in position.
- It is apparent that any interference with the pointer 43 disturbs the correct operation of the machine. Said pointer 43 being by 25 necessity a pointed piece of metal, is easily caught by the clothing of the operator or by any passing object and bent out of shape. When once so impaired it is difficult to return to accurate position. For this reason 30 the glass cover 19 of the casing is provided to render the pointer inaccessible so that no one can interfere with said pointer to impair the accurate action of the same in its alinement with the rates on the strips 41, or 35 even move said pointer except by turning the knob 52 on the exterior of the casing. This construction absolutely prevents accidental or designed displacement of the pointer and renders it possible to move said pointer by 40 turning said knob to a given position for recurring calculations.

I claim as new:—

1. In a calculating machine, a casing, a roller journaled therein, a calculating sheet wound on the roller, a rate strip arranged in the casing adjacent the roller and adapted for movement as the diameter of the roller is varied by the rolling and unrolling of the sheet thereon, a laterally movable pointer 45 extending over the strip and carried by the latter to move therewith, and means mounting the pointer whereby the indicating end of the latter is engageable with the strip.
2. In a calculating machine, a support, a roller journaled thereon, a character bearing sheet wound on the roller, and a spring rate strip mounted on the support and having a resilient edge in constant contacting relation with the sheet on the roller to yield 55 as the diameter of the latter increases on the winding of the sheet thereon.
3. In a calculating machine, a casing with a transparent top to show the parts, a frame in said casing having revoluble rollers in 60 spaced relation therein and calculating in-

dicia on said rollers, pointer operating means revolvably mounted in said frame between said spaced rollers, a balanced pointer supported on said means to be moved in either direction by the turning of said means, rate strips one each side of said means adjustable to said rollers and to said balanced pointer and support to support the latter.

4. In a calculating machine, spaced rollers, a sheet on each windable thereon, spaced spring strips interposed between the rollers in contacting relation with the respective sheets thereon, said strips yielding as the diameters of the rollers are increased by the winding of the sheets thereon, and a pointer operable between and guided by the spaced strips, said pointer moving to permit of proper yielding of the strips.

5. In a calculating machine, a frame, a roller revolvably mounted in said frame, a sheet wound around said roller, and a spring rate strip supported at each end in suitable openings in said frame which permit a limited rotative movement automatically as the diameter of the top roller increases and decreases as the sheet is wound thereon.

6. In a calculating machine, a frame having a pair of revolvably mounted rollers therein, a calculating sheet wound on said rollers to wind and unwind from one to the other, and a contacting spring rate strip alongside one of said rollers resiliently permitting increase and decrease of said roller in winding said calculating sheet thereon.

7. In a calculating machine, a casing having a transparent top, a frame in said casing having four revolvably mounted rollers in pairs therein, calculating sheets wound on said rollers onto each pair, pointer operating means between said rollers, spring rate strips one each side of said means contacting said calculating sheets on said rollers and permitting increase and decrease of said rollers from winding and unwinding 110 said sheets, and a pointer engaging said operating means to be moved thereby, said pointer slidably balanced on said means and spring rate strips to float back and forth thereon.

8. In a calculating machine, a casing having a transparent top, a frame in said casing comprising side and end plates, rollers revolvably mounted in pairs in said frame, a calculating sheet wound on each of said pairs of rollers, spring rate strips supported at each end in openings in said end plates at each side of said rollers, said rate strips cut away at each end on the side toward the rollers to permit a limited rotat- 120 ing and springing movement thereof to allow for the increase and decrease of said rollers from the winding and unwinding of said sheets, pointer operating means and a balanced pointer engaging said means to 125 130

- be moved thereby independent of said rollers, said pointer balanced on said means and spring rate strips substantially as and for the purpose specified.
5. In a calculating machine, spaced rollers, a sheet on each windable thereon, spaced spring strips interposed between the rollers in contacting relation with the respective sheets thereon, said strips yielding as the 10 diameters of the rollers are increased by the winding of the sheets thereon, and a laterally tiltable pointer movable longitudinally of the space between the strips, the latter supporting the pointer against tilting 15 and holding the same operative.
10. In a calculating machine, a casing with a transparent top to show the parts,

a frame in said casing having revoluble rollers in spaced relation therein and calculating indicia on said rollers, pointer operating 20 means revolvably mounted in said frame between said spaced rollers, a balanced pointer supported on said means to be moved in either direction by the turning of said means, and guides on each side of the means 25 movable relative to said rollers and constituting guides for the balanced pointers.

In testimony whereof I have affixed my signature in the presence of two witnesses.

CHESTER J. SMITH.
